UNITED STATES PATENT OFFICE.

WILLIAM DIETER, OF NEWARK, NEW JERSEY.

AUTOMOBILE TORPEDO.

Application filed January 28, 1926. Serial No. 84,318.

This invention introduces certain improvements pertaining to the afterbody and tail section of automobile torpedoes, such, for example, as the Bliss-Leavitt torpedo.

5 In such torpedoes the exhaust or spent gases from the turbine (or other motor) are discharged into an after-body section which constitutes an exhaust chamber, and are discharged therefrom through a bulkhead at 10 its aft end into the tail section of the automobile, from which the exhaust gases are discharged at the stern. This discharge in the standard naval torpedo occurs by passing through holes in enlarged tubular portions 15 constituting stern extensions of the inner and outer propeller shafts, these holes communicating with the chamber in the tail section and admitting flow therefrom into the inner propeller shaft from which the 20 gases are discharged at the stern end.

As applied to such torpedoes the present invention provides certain improvements in the exhaust valves which open to permit discharge of the exhaust gases and close at 25 the end of the run to prevent inflow of water and thereby cause the torpedo after a practice run to rise to the surface; and in the oil duct through which oil flows under pressure to lubricate the stern bearings of 30 the propeller shafts.

The constructions upon which the present invention provides improvements are shown with sufficient accuracy in patents of F. M. Leavitt, No. 1,076,295, dated October 21, 35 1913, and No. 1,108,196, dated August 25, 1914.

The accompanying drawing shows the adjoining portions of the afterbody and tail section of a Bliss-Leavitt torpedo constructed to embody the present invention.

Figure 1 is a fragmentary vertical longitudinal mid-section of such portions.

Fig. 2 is a transverse section on the line 2-2 in Fig. 1.

45 Fig. 3 is a fragmentary transverse section on the line 3-3 in Fig. 1.

Fig. 4 shows the parts pertaining to the exhaust valve spring separated, the enclosing parts being in mid-section.

50 Referring to the drawing, let A designate the hull or shell of the torpedo, which is subdivided into sections, the portion B constituting the afterbody and the portion C the tail section. D and E are respectively the outer and inner propeller shafts, and D' and

E' are respectively the tail sections of these shafts, which are enlarged in usual manner and provided with openings F, F' respectively, to admit flow of spent gases from the chamber G within the tail section into 60 the bore of the inner shaft E' through which the gases flow to the stern, where they are discharged into the water aft the propeller screws, all as in usual manner. The spent gases exhausted from the turbine are discharged first into the interior of the afterbody which forms an exhaust chamber H, and from this chamber they pass through the bulkhead J into the chamber G of the tail section. The openings K through which 65 they pass (one of which is shown in section in Fig. 1) are closed by exhaust valves L when the torpedo is at rest, or after it has completed its run, these valves being pressed to their seats by suitable springs and forced 70 open by the pressure of the exhaust gases during the run. Always heretofore these springs have been mounted forward of the valves and carried by the after-body and have been exposed to heat from the hot 75 exhaust gases circulating through the afterbody. To the extent of the pressure on these valves there is imposed on the gases in the chamber H a slight back pressure which is utilized to force oil out from a 80 reservoir through a suitable duct to lubricate the aft propeller shaft bearings. (This lubricating system is not here shown, but is fully shown and described in said Patent No. 1,108,196.) A portion of the oil duct 85 leading to said aft propeller bearings is shown in the accompanying drawings, being lettered M.

Such being the general known construction prior to the present invention, the features peculiar to this invention will now be described.

The exhaust valves L (two of which are shown in Fig. 2) are each mounted on a sliding stem *a* moving in a fixed bearing 95 hub *b* carried on an arm *c* fixedly mounted on a post *d* which is fixedly attached to the bulkhead J. Thus, on the separation of the tail section the parts thus described remain connected to the afterbody. A spring S for 100 the valve L is mounted in connection with the tail section and is located aft of the valve, so that upon the separation of the tail section the spring is separated from the 105 valve and is rendered accessible within the 110 valve and is rendered accessible within the

tail section. The spring is shown as a helical spring and communicates with the valve through the medium of a stem *e* which in the position of use abuts at its front end 5 against the rear end of the stem *a*. The spring *S* reacts rearwardly against any suitable abutment attached to the tail section, and presses forwardly against the stem *e* preferably by means of a collar *e'* formed 10 thereon. It is undesirable to leave the spring *S* exposed in the chamber *G*, because this chamber is filled with the hot exhaust gases which would in time be apt to impair the temper of the spring. It is also desirable to 15 effectually lubricate the stem *e* which is mounted in sliding bearings. These results are attained by enclosing the spring in an oil chamber *f* which itself is enclosed in a water chamber *g* through which a circulation 20 of cool sea water from the exterior is maintained during the run of the torpedo. These chambers in the preferred construction shown are provided as follows: A tubular shell *h* is formed with two water passages *i* and *j* terminating in suitable flanges *y*, whereby it is fastened to the outer shell *A* of the tail section. The passages *i*, *j* communicate with coinciding holes *i'*, *j'* in this shell so as to be in free communication with 25 the sea water in which the torpedo is traveling. The motion of the torpedo induces a current of water which enters through one of these passages, circulates through the inner chamber *g*, and flows out through the 30 other passage.

Within the shell *h* thus described, is introduced an inner shell *k* (Fig. 4) having in one end an opening *k'* through which the stem *e* freely slides, and closed at the other 40 end by a cap or plug *l* having a similar hole *l'* receiving the stem *e*. This inner shell *k* is preferably screwed into one end of the shell *h*, as shown, whereby that end of the latter is closed. Its other end may 45 be closed by a disk *k'*, or in any other convenient way. The spring *S* presses against the flange *e'* and reacts rearwardly against the screw plug *l*. Upon assembling the parts within the shell *h* the chamber *f* is filled 50 with oil for lubricating the stem *e*. The stem *e* slides freely within the holes *k'*, *l'*, and, being of equal diameter in each, its movement occasions no change in the capacity of the oil chamber *f*, and consequently 55 no oil is expelled by its movements, the oil simply circulating within the chamber *f*. Thus the spring is kept immersed in oil, which, if it is a steel spring, prevents its rusting; while the oil also lubricates the 60 stem; and as there is no pressure tending to expel the oil (since the fluid pressures at opposite ends are balanced) a single charge of oil should remain in this chamber indefinitely.

65 It results from this feature of construc-

tion that the spring is not only enclosed in an oil chamber, but is kept cool by the circulation around this oil chamber of water at the normal temperature of sea water, which is kept flowing through the outer 70 chamber or jacket *g*.

One of the advantages of this construction is that the valve *L* is given a straight line movement which causes it, when forced open, to afford an equal annular passage all 75 around for the escape of gases, thereby utilizing in full the outflow area of the port. The stem *e* and spring being also aligned with the stem *a*, the spring stress is exerted in line with the movement of the valve *L* so that it is most effectively applied. When the tail section is separated from the afterbody, the valve *L* remains carried by the latter, and the spring chamber and stem *e* are carried by the tail section; when the tail section is replaced, the act of attaching it to the afterbody necessarily brings the stems *e* and *a* into alignment, and by this act the stem *e* is slightly displaced (to the position shown in Fig. 1), whereby to bring the spring stress to bear upon the valve *L* and hold it seated. When the valve *L* is forced open the stem *e* is pressed back, this movement merely displacing a small amount of water from the water chamber within the shell *h*, the effect of which is negligible.

The parts are easily disassembled by unscrewing the shell *h* from the shell *h* after which the plug *l* may be unscrewed to remove the spring and stem *e*.

The oil duct *M* for conducting oil from an oil cup or reservoir (not shown) in the afterbody through the bulkhead *J* and the joint between the afterbody and tail section, and to the propeller shaft aft bearings (not shown), involves a novel construction designed to facilitate the separation and reconnection with the afterbody and tail section. (The parts not here shown are of usual construction and are clearly illustrated in said Patent No. 1,108,196.) The oil duct *M* is provided with the usual check valve *P* to prevent back-flow of oil, but this valve, instead of being mounted in the tail section as heretofore, is now located in the afterbody, its construction otherwise being not necessarily changed. From this valve the oil duct *M* is formed as a tube *m* (preferably of copper) leading to a nipple *n* which passes through the bulkhead *J* and receives a cap *p*, whereby it is confined to the bulkhead, and which cap also serves as a terminal facing or seating *q*. In the working position aligned with this and pressed into leak-tight contact therewith is a seating connection or piston *r* appurtenant to a fitting or shell *Q* which is fastened within the tail section. This part *Q* has within it a combined spring chamber and oil chamber *t* enclosing a spring *s*. From the oil chamber *t* 130

5 a tube *u* forming a continuation of the oil duct *M* leads aft and extends ultimately to the propeller shaft bearings as heretofore. Between the fittings *p* and *r* is a seating 10 packing or gasket *v* which may be carried by either part, being shown as applied to the cap *p*. The fitting *r* is pressed against *p* by the stress of the spring *s* which acts forwardly against the piston *r* and reacts rearwardly against a shoulder in the part *Q*. The piston *r* has a reduced stem *w* extending rearwardly and projecting through the fitting *Q* and receiving a cotter pin *x* which, when the parts are separated, prevents the 15 piston being pressed too far forward by the spring *s*. The piston *r* and its stem *w* are bored out tubularly to form a portion of the oil duct from which the oil flows through lateral perforations in the stem into the oil 20 chamber *t*, and thence out through the tube *u*.

When the tail section is separated from the afterbody the piston *r* is carried away with the tail section. When the tail section 25 is replaced, the piston is brought back into coincident alignment with the terminal fitting *p*, and the uniting of the tail section brings it into position to press back the piston *r* against the spring *s* so that the 30 stress of the spring is exerted to hold the parts *r*, *p* pressed together, whereby to make a tight joint between them with the aid of the gasket *v*.

The spring *s* being enclosed in a chamber 35 *t* through which oil is constantly flowing during the run of the torpedo, is not only protected against rust, but is also kept so cool as not to impair its temper.

This construction is practically an important 40 improvement over that heretofore used, in which much difficulty has been encountered in bringing the parts of the oil duct carried respectively by the afterbody and tail section together in proper communication 45 when the tail section was applied to the afterbody. It has sometimes resulted that the parts were put together without the sections of the oil duct being thus brought into communication, so that there 50 was no conduction of oil from its source in the afterbody to the propeller shaft bearings, with the result that these bearings were not lubricated and serious damage resulted.

55 The invention is susceptible of a reasonable degree of modification within the scope of the appended claims.

I claim as my invention:

60 1. In an automobile torpedo having a transverse bulkhead with an exhaust opening through it, an exhaust valve to close said opening, and a spring carried by the tail section and located on the aft side of said bulkhead to close said valve.

65 2. In an automobile torpedo having a

transverse bulkhead with an exhaust opening through it, an exhaust valve to close said opening, a sliding stem for said valve, a support in which said stem slides, and a spring aft of the bulkhead carried by the 70 tail section and pressing forwardly against said stem to close the valve.

3. In an automobile torpedo, an exhaust valve having a straight line movement with a spring on its aft side carried by the tail 75 section and exerting forward pressure to close the valve.

4. In an automobile torpedo having an afterbody and tail section, an exhaust valve carried by the afterbody and a spring for 80 closing said valve carried by the tail section, and separable from the valve on removing the tail section.

5. In an automobile torpedo having an afterbody and tail section, an exhaust valve 85 carried by the afterbody and a spring-pressed stem carried by the tail section adapted when the sections are united to engage the valve to close it.

6. In an automobile torpedo, an exhaust 90 valve and a spring for closing said valve, with means for water-cooling said spring during the run of the torpedo.

7. In an automobile torpedo, an exhaust valve and a spring for closing said valve, 95 with a chamber enclosing said spring having communication with the exterior to admit water to cool the spring.

8. In an automobile torpedo, an exhaust valve and a spring for closing said valve, 100 with an oil chamber enclosing said spring.

9. In an automobile torpedo, an exhaust valve and a spring for closing said valve, with an oil chamber enclosing said spring, and a water chamber enclosing said oil 105 chamber for cooling the latter.

10. In an automobile torpedo, an exhaust valve, a spring for closing it, a stem transmitting the stress of said spring to said valve, an oil chamber enclosing said spring, 110 and into which said stem projects, and a water-cooling chamber enclosing said oil chamber.

11. In an automobile torpedo having an afterbody and tail section, an exhaust valve 115 carried by the afterbody, a spring for closing said valve, a shell carried by the tail section forming a water chamber, a shell enclosed therein and enclosing said spring, and a stem working in said latter shell and 120 communicating stress from the spring to the valve.

12. In an automobile torpedo having an afterbody and tail section, an exhaust valve carried by the afterbody and having a sliding stem, a spring therefor, and a sliding stem, both carried by the tail section and adapted upon the connection of the tail section with the afterbody to bring said stem 125 into alignment and contact with the valve 130

stem, whereby to transmit stress from said spring to the valve.

13. In an automobile torpedo having an afterbody, a transverse bulkhead, and a tail section removably attached to the afterbody, with lubricating means comprising an oil duct passing through the bulkhead and having portions carried by the afterbody and tail section respectively, with a separable connection between such portions comprising a member mounted on the afterbody and a member carried by the tail section, adapted to come into abutment on the union of said parts.

14. In an automobile torpedo having an afterbody closed at its aft side by a bulkhead, and a tail section removably attached thereto, with lubricating means comprising an oil duct passing through the bulkhead and having portions carried by the afterbody and tail section respectively, with a separable connection between such portions comprising a member mounted on the bulkhead and a member carried by the tail section, adapted to come into abutment on the union of said parts, and one member spring-pressed against the other to make a close joint between them by the act of uniting the tail section to the afterbody.

15. In an automobile torpedo, lubricating means according to claim 13, one of said

members formed as a spring-pressed sliding piston.

16. In an automobile torpedo, lubricating means according to claim 13, a spring for pressing one member against the other, and means for cooling said spring.

17. In an automobile torpedo, lubricating means according to claim 13, a spring for pressing one member against the other, and an oil chamber enclosing said spring and through which the oil flows, whereby the spring is cooled.

18. In an automobile torpedo, lubricating means according to claim 13, one of said members formed as a sliding piston having a projecting rod, a chamber carried by the tail section enclosing said piston, a spring within said chamber pressing against said piston, said rod emerging from said chamber, and a stop on said rod for limiting the projection of the piston when the tail section is disconnected.

19. In an automobile torpedo, lubricating means according to claim 13, and a check valve in connection with the oil duct for preventing back-flow, said check valve carried by the afterbody.

In witness whereof, I have hereunto signed my name.

WILLIAM DIETER.
